DUPLICATING MACHINE

Charles H. Bradt, Groton, N. Y., assignor to L. C. Smith & Corona Typewriters, Inc., Syracuse, N. Y., a corporation of New York

Application March 19, 1942, Serial No. 435,383

4 Claims. (Cl. 101—132.5)

The invention relates to improvements in duplicating machines, and more particularly to duplicating machines for making copies by the wet or spirit process of hectographic duplication.

The invention has for its principal object the provision of improved means for feeding and moistening copy sheets in machines of the kind above referred to.

Another object of the invention is to provide an improved moistening means automatically controlled to substantially entirely prevent undesirable application of ink solvent to parts of the machine when no copy sheet is in place to receive solvent from the solvent applying member of the moistening mechanism.

A further object is to provide a spirit process duplicator having an ink solvent receiving and applying roller which is controlled by the copy sheets to apply solvent to each sheet substantially from end to end irrespective of the length of the sheet and to substantially prevent application of solvent by said roller to an opposed sheet feed roller while no sheet is interposed between the applying roller and opposed roller.

A further object is to provide an improved construction of rotary duplicator of the spirit process type permitting printing substantially from end to end of copy sheets of lengths equal to or less than the circumference of the master sheet carrying drum or cylinder of the machine, and permitting repeated copying of the matter on the master sheet upon a web of indefinite length.

A specific object of the invention is to provide a spirit process duplicator of the rotary type having solvent applying means with the improved characteristics above pointed out and wherein the time of initial printing contact of a solvent coated copy sheet with a master on a rotating drum of the machine is adjustably variable to initiate such contact at any point around the axis of the drum.

Other objects and advantages of the invention will appear from the following description of a preferred embodiment of the invention shown in the accompanying drawings, in which:

Figure 1 is a fragmentary side elevation looking at the right hand side of the machine.

Figure 2 is a detail sectional view on the line 2—2 of Figure 1.

Figure 3 is a detail view illustrating an action of a part of the mechanism hereinafter further described.

Figure 4 is a detail sectional view on the line 4—4 of Figure 3.

Figure 5 is a fragmentary sectional view taken approximately on the line 5—5 of Figure 1.

Figures 6, 7 and 8 are detail sectional views approximately on the line 6—6 of Figure 2 illustrating the operation of a part of the machine.

The improvements embodying the present invention in its preferred form are shown incorporated in a machine otherwise constructed substantially as disclosed in Patent No. 2,185,188, granted January 2, 1940, to John J. Flanigan. Only so much of the known machine as is necessary for an understanding of the present invention has been illustrated in the drawings and will be described, and reference may be had to said patent for further details of the patented machine incorporated in the improved machine embodying the present invention.

The main framework of the machine includes a suitable base 10 and upstanding left and right hand vertical side walls 11 and 12 rigidly held to said base. The duplicating drum or cylinder 13 is fixed on a drive shaft 14 which is journaled in suitable bearings carried by the side walls of the frame, one of said bearings being shown at 15 in Figure 2. Shaft 14 is continuously rotated in the direction indicated by the arrow in Figure 1 during operation of the machine, and the drum is provided with a narrow, longitudinal slot 16 in which, in using the machine, the leading end of a master sheet is secured for taking copies from said sheet. The usual platen roll 17 is maintained in constant contact with the under part of the drum 13 and is tractively driven by the drum.

A suitable copy sheet feed table 18 is fixedly mounted on base 10 at the forward end of the machine. The rear end of the feed table is located closely in front of the bight of the known pair of superposed introductory feed rolls 19 and 20 of the machine. The lower roll 20 is journaled in the frame for rotation about a fixed horizontal axis. The upper roll 19 is journaled in the known rocking frame 21 for rotation about a horizontal axis, said frame being rockable about a horizontal axis at 22 to raise and lower roll 19 out of and into contact with roll 20. A spring 23 connected to wall 12 and frame 21 normally tends to maintain roll 19 in yielding contact with roll 20. The rolls 19 and 20 are formed with the known series of circumferential registering grooves 24.

The known series of sheet registering stop fingers 25 are mounted and actuated in the known manner by the known means disclosed in said

patent, the forward ends of said fingers working in the grooves 24 of rolls 19 and 20 in the known manner. The supporting and controlling means for the stops 25 includes the usual rocking frame comprising rock shaft 26 journaled in the side plates, the cross rod 27 swingable bodily by the shaft about the shaft, rock arm 28 fixed on shaft 26 and carrying a tappet 29. A spring 30 connected to arm 28 and plate 12 normally urges rod 27 downward. Stops 25 are loosely mounted on rock shaft 26 with their rear arms urged upward against rod 27 by the usual springs 31 as more fully disclosed in said patent.

The rocking frame 21 carries the usual tappet 32, which tappet and the tappet 29 on rock arm 28 are both engaged over the forwardly extending arm of the known actuating lever 33 fulcrumed on the frame at 34 and carrying the usual cam follower roll 35 on its rear arm. Lever 33 is rocked by the usual main cam 36 held to shaft 14 to rotate in unison with drum 13. The follower 35 rides on the periphery of cam 36 which has the known long high dwell edge portion 36^a and short low dwell edge portion 36^b.

As in the patented machine referred to, a moistening fluid or ink solvent is maintained at a constant level in a trough 37 mounted on the frame and extending horizontally between plates 11 and 12 above and rearward of the pair of introductory feed rolls 19 and 20. The known metallic fountain or supply roll 38 is journaled in the side plates for rotation about a fixed horizontal axis 39 with the lower part of the roll within the trough 37. Roll 38 has in its periphery a narrow and shallow helical groove 40. The metallic roll 41 for applying the ink solvent to the copy sheets is, as in the machine of said patent, journaled in a pair of rock arms 42 having pin and slot sliding pivotal connections 43 with the side plates 11 and 12, and springs 44 anchored to said arms and plates to maintain roll 41 in constant contact with roll 38 and to constantly yieldingly tend to maintain roll 41 in contact with the usual counter-pressure feed roll 45. Roll 45 is journaled in the frame side plates to rotate about a fixed horizontal axis 46, the bight of the superposed rolls 41 and 45 being located to the rear of the bight of the pair of rolls 19 and 20 and forward of the bight of the drum 13 and platen roll 17.

Journaled in plates 11 and 12 behind roll 41 is a horizontal rock shaft 47 having fixed thereto, and extending forwardly therefrom under the free ends of rock arms 42, a pair of rock arms 48 constantly maintained in contact with arms 42 by a light spring 49 which is of insufficient strength to overcome the weight of roll 41, and arms 42 and the pull of springs 44. Extending vertically entirely across the inner face of the right hand rock arm 48 is a channel 50.

As in the machine of said patent there is provided a prop coactive with the right hand rock arm 48 under control of a copy sheet detector means constructed as will now be briefly described. A horizontal rock shaft 51 journaled in plates 11 and 12 has rigid therewith a series or row of copy sheet detector pins or feelers 52 which normally extend upward and rearward from shaft 51 across the path of travel of the copy sheets and in between the stops of the row of copy sheet arresting stops 25 as indicated in Figure 8. Fixed on the right hand end of shaft 51 is a pendent rock arm 53 normally yieldingly held in the position shown in Figures 1 and 8 by a light spring 54 anchored to arm 53 and plate 12. An 75

upstanding prop or lever 55, fulcrumed substantially midway its ends on plate 12 at 56 to swing fore and aft of the machine, has its lower arm connected to arm 53 by a rigid link 57 pivoted to both arms to effect movement of said arms in unison and in substantial parallelism. The upper end of the prop lever 55 is adapted either to be received freely in channel 50 in right hand rock arm 48 (as indicated in Figure 7) to permit roll 41 to contact roll 45 (or rather, a copy sheet between said rolls), or to be interposed normally under said arm 48 at the forward edge of channel 50 (as indicated in Figure 8) to prevent roll 41 from moving down into contact with roll 45.

15 It will be understood that the drum and the various rolls described are driven as and by the means disclosed in the prior patent above referred to, the peripheral speed of all the rolls corresponding to that of the drum. Viewing the machine as in Figure 1, the drum 13, roll 41 and roll 19 have a counterclockwise rotation, whereas the platen roll 17, roll 38, roll 20 and roll 45 have a clockwise rotation. The drum 13, roll 38 and roll 20 are positively driven continuously from a suitable source of hand or motive power. Roll 41 is constantly tractively driven by roll 38. The platen roll 17 is constantly tractively driven by drum 13. Roll 19 when lowered is tractively driven by roll 20, and roll 45 is tractively driven by roll 41 when the latter is lowered.

The new features of construction of the machine illustrated in the accompanying drawings will now be described.

The cam 36 is releasable from shaft 14 for rotative adjustment of the cam in either direction about the shaft relatively to drum 13 through a complete circuit of 360 degrees, and may be locked to the shaft in any rotatively adjusted position within said circuit to change the timing of the machine. The cam 36 is fixed on the inner end of a sleeve 58 freely rotative about shaft 14, said sleeve having a finger knob 59 fixed on its outer end. A friction washer 60, loosely encircling shaft 14 and seated in a circular recess 66 in the outer face of knob 59, is adapted to have pressed tightly thereagainst a flexible friction disk 61 keyed to shaft 14 by a pin 62. A clamping nut 63, threaded on the adjacent end of shaft 14 and contacting disk 61, is oppositely rotative to frictionally lock the cam to the shaft to rotate with the shaft or to release the friction grip to permit rotative adjustment of the cam. When locked, the cam and sleeve are pressed against an abutment or collar 64 fixed on the shaft 14 by a pin 65.

55 Suitable graduation marks 67 are preferably provided on the outer face of knob 59 around recess 66 and a coactive graduation mark or pointer line 68 is preferably provided on the exposed outer face of disk 61. One of the graduations 67 preferably has the designation "0" associated therewith on the knob as indicated at 69.

Drum shaft 14 extends loosely through a mutilated ratchet wheel 70 and a mutilated rigid disk 71 which are located between wall 12 and cam 36 and are in facewise abutment with the disk located nearest the cam. Ratchet wheel 70 and disk 71 are coaxial with the drum and cam 36 and are rigidly held to cam 36 to rotate therewith by means of bolt and nut fastenings 72 and spacing sleeves 73. The diameter of the disk 71 is somewhat less than the diameter of the ratchet wheel at the roots or bases of the wheel teeth. For a short distance therearound the periphery of the ratchet and the periphery of the disk are cut 70 away to within the same distance from their axes

to provide axially registering recesses as indicated at 14 located within the angle which includes the low dwell edge portion 36^b of cam 36. Immediately in advance of the recess therein, the disk 71 has formed on its periphery a small cam hump 75.

Extending rearward from and fixed to rock shaft 47 at the right hand side of the machine is a rock arm 16 on which is pivoted on a horizontal axis at 11 a normally upstanding pawl or dog 78, the nose 78^a of which is engageable with ratchet 70 and is formed on the upper arm of the pawl. The lower arm of the pawl has fixed thereto a laterally extending pin 79 engaged in a longitudinal slot 80 formed in a link 81 which extends rearwardly from and is pivoted at 82 to the upper arm of the prop lever 55. A spring 83 normally urges the pawl about its pivot into a position in which pin 79 is at the rear end of slot 80. Rock arm 16 is provided to the rear of pawl 78 with a laterally extending pin 84 engageable by the upper arm of the pawl to limit rearward rocking of said arm about pivot 11. Journaled on the upper end of the pawl on a horizontal axis at 85 is a small metal roll 86 coactive with the periphery of disk 71.

Operation

During each revolution of the drum, roll 19 is raised and lowered and stops 25 are moved into and out of sheet arresting position, the stops being out of sheet arresting position while roll 19 is lowered and being in sheet arresting position while roll 19 is raised from roll 20. When no copy sheet is engaged with the sheet detector, the prop 55 remains in the position shown in Figure 8 and the pawl 78 and its roll 86 will thus be held rocked relatively to arm 16 in the position shown in dotted lines in Figure 8 and the solvent applying roll 41 cannot move downward into contact with roll 45. Immediately after roll 19 is lowered, during each revolution of the drum and at a time varying with the rotatively adjusted position with respect to the drum of cam 36, ratchet wheel 70 and disk 71, the cam hump 75 engages roll or follower 86 on pawl 78 and rocks shaft 47 as shown in Figure 6 to lift roll 41 still farther to free prop 55 of pressure from the weight of roll 41. If no sheet has been introduced into the machine, the roll 41 will re-assume the position shown in Figure 8 after hump 75 passes the roll 86. Consequently, it will be seen that, as long as no copy sheets are fed into the machine, roll 41 will be kept out of contact with roll 45 and roll 86 on pawl 78 will be kept in the path of cam hump 75.

If a copy sheet is introduced into the machine against stops 25 while roll 19 is elevated, the sheet will be advanced upon lowering of said roll and will, while hump 75 is passing roll 86, engage the detector and shift the latter and prop 55 into the position shown in Figure 6 whereupon roll 41 will lower into contact with the leading end of the copy sheet as shown in Figure 7 and will remain lowered until the trailing end of the copy sheet passes from the detector fingers 52. In the position of the parts shown in Figure 7, it will be observed that link 81 is moved rearward into a position in which spring 83 has rocked pawl 78 to move and hold the nose 78^a of pawl 78 forward away from ratchet wheel 70 and to move and hold roll 86 forward out of the path of cam hump 75, thus disabling the lifting mechanism for the solvent applying roll until the copy sheet completes its transit past fingers 52.

As soon as the trailing end of the copy sheet passes fingers 52, link 81 will again be drawn forward by the pull of spring 83 to permit engagement of the nose of the pawl 78 with the 5 toothed periphery of ratchet wheel 70 as indicated in Figure 3, whereupon the rotating ratchet wheel will rock the pawl against pin 84 and depress arm 16 to elevate roll 41 substantially to the 10 position shown in Figure 6 and the detector and prop will then move into the position shown in Figure 8. As the nose of the pawl leaves the ratchet wheel and the pawl assumes the position shown in full lines in Figure 8, arm 48 will lower slightly into contact with the top end of prop 55, 15 and the roll 86 will engage the periphery of disk 71 as shown in Figure 8 to retain the pawl in the position shown in Figure 8 for subsequent action of hump 75 on roll 86 and the pawl. The timing is such that roll 41 will lower on the extreme leading end of a copy sheet and will only lift substantially at the time that the extreme trailing end of the sheet reaches the bight of rolls 41 and 45.

If the trailing end of a copy sheet or web 25 should pass off of fingers 52 while recesses 14 are passing pawl 78, there will, of course, be a slightly delayed action of the lifting and locking up of roll 41. Since the disk 71 and ratchet wheel 70 are 30 adjustable bodily with the timing cam 36 relatively to the drum about the drum axis to any angularly adjusted relation to the drum slot 16, it will be obvious that the leading end of a sheet may be timed to enter the bight of the drum 13 and platen roller 17 with slot 16 at any rotated 35 position with respect to said bight, but that any copy sheet or web fed into the machine will nevertheless have a continuous coating of ink solvent applied to its upper face substantially from end to end of the sheet or web. If a sheet or web 40 several times as long as the circumference of the drum be fed into the machine, its upper face will have ink solvent applied thereto without interruption no matter how many revolutions of the drum are required to feed said sheet or web between the drum and platen roller for printing, 45 and said sheet or web will thus be conditioned to receive repeated impressions of the matter delineated on the master carried by the drum.

The registering recesses 14 in the ratchet 70 and disk 71 free the pawl 78 to assume the position shown in Figure 7 while a sheet is being fed through the machine over fingers 52. If the drum is rotated without feeding copy sheets, the pawl vibrates about its pivot from the position shown 55 in full lines in Figure 8 to the position shown in dotted lines in Figure 8 and back again each time cam hump 75 and the recesses 14 pass the pawl, and link 81 prevents the roll 86 on the pawl from remaining out of the path of hump 75. The contact of roll 86 with disk 71 also prevents noise which would result if the pawl contacted the ratchet while roll 41 is elevated.

I claim:

1. A duplicating machine of the class described comprising a rotative master sheet carrying drum, a platen roll coactive with the drum, a pair of copy sheet feed rolls for advancing copy sheets toward the bight of the drum and platen roll, 60 means for supplying ink solvent to one of said rolls, means shiftable to separate said feed rolls, a latch normally coactive with said shiftable means to hold the feed rolls separated, means operable by a copy sheet to release said latch as 65 the leading end of the sheet reaches said pair of

rolls, a ratchet rotative with the drum, a pawl on said shiftable means normally retracted from said ratchet and movable by said sheet operable means into contact with said ratchet to actuate the shiftable means to separate the feed rolls as a copy sheet completes its transit between said rolls.

2. A duplicating machine of the class described comprising a rotative master sheet carrying drum, a platen roll coactive with the drum, a pair of copy sheet feed rolls for advancing copy sheets toward the bight of the drum and platen roll, means for supplying ink solvent to one of said rolls, means shiftable to separate said feed rolls, a latch normally coactive with said shiftable means to hold the feed rolls separated, means operable by a copy sheet to release said latch as the leading end of the sheet reaches said pair of rolls, a ratchet rotative with the drum, a pawl on said shiftable means normally retracted from said ratchet and movable by said sheet operable means into contact with said ratchet to actuate the shiftable means to separate the feed rolls as a copy sheet completes its transit between said rolls, and means rotative with the drum and engageable with the pawl when the feed rolls are separated to relieve binding engagement between the latch and shiftable means at a predetermined point in the revolution of the drum.

3. In a duplicating machine of the kind having a rotatively driven printing drum and copy sheet feed means periodically operable to advance sheets toward the drum in timed relation to the rotation of the drum, the combination with said drum and feed means of means for moistening each sheet advanced toward the drum by said feed means comprising a moisture applying roll, parallel to and in advance of the drum, an underlying counter pressure roll for the applying roll rotative about a fixed axis parallel to the drum axis, a lifter rockable about a horizontal axis to raise the applying roll from the counter pressure roll and having an arm extending rearward from the pivotal axis of the lifter, a mutilated ratchet wheel rotative with the drum about the drum axis, a pawl pivoted on said arm to swing into and out of engagement with said ratchet wheel, a spring normally urging said pawl from the ratchet, means limiting swinging of the pawl in opposition to said spring, a lifter prop swingable about an axis parallel to that of the lifter and

constantly spring urged toward a position to hold the lifter in applier roll elevating position, a copy sheet detector in advance of the applier and counter pressure roll and connected with said prop to maintain the prop in ineffective position during engagement of a sheet with the detector, and means connecting the prop and pawl to temporarily engage the pawl with the mutilated ratchet, substantially when a copy sheet completes its transit past the detector, to cause lifting of the lifter for engagement of the prop thereunder.

4. In a duplicating machine of the kind having a rotatively driven printing drum and copy sheet feed means periodically operable to advance sheets toward the drum in timed relation to the rotation of the drum, the combination with said drum and feed means of means for moistening each sheet advanced toward the drum by said feed means comprising a moisture applying roll, parallel to and in advance of the drum, an underlying counter pressure roll for the applying roll rotative about a fixed axis parallel to the drum axis, a lifter rockable about a horizontal axis to raise the applying roll from the counter pressure roll and having an arm extending rearward from the pivotal axis of the lifter, a mutilated ratchet wheel rotative with the drum about the drum axis, a pawl pivoted on said arm to swing into and out of engagement with said ratchet wheel, a spring normally urging said pawl from the ratchet, means limiting swinging of the pawl in opposition to said spring, a lifter prop swingable about an axis parallel to that of the lifter and constantly spring urged toward a position to hold the lifter in applier roll elevating position, a copy sheet detector in advance of the applier and counter pressure roll and connected with said prop to maintain the prop in ineffective position during engagement of a sheet with the detector, and means connecting the prop and pawl to temporarily engage the pawl with the mutilated ratchet substantially when a copy sheet completes its transit past the detector, to cause lifting of the lifter for engagement of the prop thereunder, and a mutilated cam rotative with the ratchet and drum and coactive with the pawl to raise the lifter from the prop as a copy sheet reaches the detector.

CHARLES H. BRADT.
